UNITED STATES PATENT OFFICE.

NATHAN H. SUREN, OF NEEDHAM, MASSACHUSETTS, ASSIGNOR TO GAMEWELL FIRE ALARM TELEGRAPH COMPANY, OF NEWTON UPPER FALLS, MASSACHUSETTS, A CORPORATION OF NEW YORK.

FIRE-ALARM SYSTEM.

Application filed April 4, 1919. Serial No. 287,502.

To all whom it may concern:

Be it known that I, NATHAN H. SUREN, a citizen of the United States, and a resident of Needham, in the county of Norfolk and Commonwealth of Massachusetts, have invented an Improvement in Fire-Alarm Systems, of which the following description, in connection with the accompanying drawings, is a specification, like characters on the drawings representing like parts.

This invention relates to fire-alarm systems and more particularly to auxiliary fire-alarm systems whereby signaling mechanism in the main circuit is adapted to be actuated from one or more stations on the auxiliary circuit.

One object of the invention is to provide means for automatically differentiating between an intentional or emergency signal transmitted from one of the stations on the auxiliary circuit and a signal which is the result of a line fault, such as the breaking of the auxiliary circuit, and to provide means whereby the occurrence of a line fault may be signalled to the central station by means of some specific signal indicating such fault.

This and other objects of the invention will be best understood by reference to the following description when taken in connection with the accompanying illustration of one specific embodiment thereof, while its scope will be more particularly pointed out in the appended claims.

In the drawings:

Fig. 1 shows in front elevation of a usual type of street fire-alarm box to which is applied one specific form of box-pulling attachment which may be used in carrying out the invention;

Fig. 2 is a wiring diagram showing the location of the fire-alarm box illustrated in Fig. 1 in a typical, main fire-alarm circuit and its connection to the auxiliary circuit;

Fig. 2^a is a diagrammatic representation of one of the signaling switches;

Fig. 3 is a side elevation, partially in section, of the parts constituting the auxiliary box-pulling attachment, these parts being shown on a somewhat larger scale than in Fig. 1;

Fig. 4 is a sectional elevation taken on the line 4—4 in Fig. 3, looking in the direc-

tion of the arrow, and showing the release lever for the main drum;

Fig. 5 is a section in plan on the line 5—5 in Fig. 3 showing the relation of the armature and armature lever to the starting magnet;

Fig. 6 is a sectional elevation taken on the line 6—6 in Fig. 3, looking in the direction of the arrow, and showing the box-starting parts and controlling cam therefor;

Fig. 7 is a sectional elevation taken on the line 7—7 in Fig. 3, looking in the direction of the arrow, and showing the cam and other parts for controlling the sending of the specific signal;

Fig. 8 is an elevation in section taken on the line 8—8 looking in the direction of the arrow, and showing the operation of the shunt lever and other related parts; and

Fig. 9 is a partial side elevation showing the parts for operating the indicator.

Referring to the drawings and particularly to Figs. 1 and 2, I have there shown conventionally for illustrative purposes, a main fire-alarm circuit 10 passing from the central station 11 and including thereat a battery or other source of current 12.

Included in the main circuit, there are also provided one or more signaling stations at which there is located suitable signaling mechanism including a signaling train, one such station being indicated at 13 and others at 14, 15, and 16, and each one being adapted, when actuated, to transmit to the central station its individual signal.

The signaling box at the station 13 has the casing 17 within which there is contained any usual or suitable signaling mechanism. The specific construction of this apparatus is immaterial, but as typifying a usual mechanism of this kind, I have herein indicated conventionally and diagrammatically the working parts of a common form of signaling train which is adapted to be released and set into operation to transmit its signal by the depression of the starting lever 18. The latter may be operated by any of the usual manual pull devices,

but herein, either in conjunction with or to the exclusion of a manual operation, the pull lever may be depressed and the train released by the bell-crank tripping lever 19.

The lower end of the latter bears against the upper edge of the lever 18, while its upper arm is jointed to the box-tripping link 20 which latter is adapted to be pushed 5 to trip the box by the auxiliary magnet 21 acting through suitable mechanism to be hereinafter described.

Referring now to the electrical connections, the auxiliary magnet 21 is not only 10 in the main circuit but is also in a shunt or auxiliary circuit 22 (Fig. 2) which extends from the master box or station 13 and has one or more emergency signaling stations arranged at intervals and provided each 15 with a switch 23, by means of any one of which, as will be described, the master box 13 may be actuated and the characteristic signal of that particular box transmitted to the central station.

20 The main circuit 10, therefore, leads from the central station to one side of the auxiliary magnet 21, which is normally shunted by the auxiliary circuit 22, thence through the shunt, the current mainly passing to the 25 other side of the magnet and through the conductor 26 and the normally closed contacts 27. Thence it passes through the normally closed signaling contacts 28 controlled by the signaling train and through the non- 30 interfering magnet 29 to the box terminal 30, whence it leads through the other master boxes in succession and back to the central station. The remaining boxes, if desired, may be equipped with auxiliary actuating 35 mechanism and auxiliary circuiting similar to that associated with the box 13.

In the illustrative embodiment of the invention, the auxiliary circuit 22 is normally closed around the auxiliary or starting magnet 21, and the latter, owing to its relatively 40 high resistance, receives so small a proportion of the main line current as to prevent its effective energization. If the auxiliary circuit, however, is broken, as by opening 45 the switch 23 at one of the signaling stations, the starting magnet 21 is energized by the full main line current which thereupon passes through the same.

In the illustrative form of the invention, 50 the construction is such that if the auxiliary circuit is broken intentionally by movement of one of the signaling switches 23, the master box is immediately actuated to give its characteristic signal. But if the auxiliary circuit is broken accidentally, a specific signal 55 only is transmitted to the central station indicating a fault in one of the auxiliary circuits. According to the adjustment or construction of the device, this specific signal may or may not be followed by the characteristic box signal thereby indicating in 60 which particular auxiliary circuit on the system the fault has occurred.

For this purpose, the switches 23, at the 65 auxiliary circuit signaling stations, which

switches are herein only conventionally shown, are so constructed that when any switch is moved it breaks the auxiliary circuit, but is directly thereafter released and returned to its normal circuit-closing position, thereby restoring the circuit and permitting a temporary energization only of the starting magnet 21.

In Fig. 2^a such a switch is diagrammatically indicated, the switch being normally held in closed position against a stop 158 by means of the spring 160. When the switch arm is depressed to open the circuit it is automatically closed by the spring, but only after the lapse of a predetermined time 80 interval which is determined by the dash pot 161, or other equivalent device, connected to the switch arm to retard its return to its closed position. The devices controlled by the starting apparatus are so constructed 85 that they automatically differentiate through the signals transmitted between such a temporary energization of the starting magnet resulting from an emergency signal in the auxiliary circuit and a persisting energization of the magnet resulting 90 from an accidental break therein.

Referring now to the devices which are actuated by the starting magnet, the latter and its associated parts are mounted upon a 95 segmental frame or casting 40 secured to the side of the casing 17 and presenting bearings 41, 42 in which a main shaft 43 (see Fig. 4) is adapted to turn. A motive device for starting the box is provided in the 100 form of the main drum 44, mounted on the shaft and connected thereto by means of a flat coiled spring 45, one end of which is secured to the interior of the drum and the other end to a hub 46 upon the shaft.

The apparatus is placed in its "set" condition, as will more fully appear, by turning the shaft 43 through a suitable turning key applied to the squared end 47 of the shaft and thereby winding up or tensioning the 110^a spring 45. The drum, which is normally held against movement, is then adapted to turn left-handedly as viewed in Fig. 4, or right-handedly as viewed in Figs. 6 and 7. as soon as suitable releasing mechanism is 115 set into operation by the energization of the starting magnet 21.

Referring to Figs. 3 and 4, the drum is provided at one circumferential edge with the gear 63, adapted to mesh with the pinion 64, connected to the pallet wheel 65 on the pallet wheel shaft 66, the pallet wheel having engaged therewith a pallet 67 of such construction that the drum in its rotation is given a retarded or time-controlled movement.

The pallet wheel and drum are normally held against movement by a stop pin 68, carried by the releasing lever 51, pivoted at 52 on the frame. This stop pin normally 125

engages a similar pin 69 on the pallet wheel 65, and when thus engaged a pin 50 projecting laterally from the upper end of the lever 51 enters a slot formed in an annular flange 53, projecting from the back of the drum. The pin 50 is of triangular cross-section, and the slot on the flange 53 has an inclined wall below the pin as seen in Fig. 4. When the releasing lever is moved to a position of release by the armature lever as hereinafter described, it carries the stop pin 68 out of the path of the pallet wheel 69 and the latter starts to revolve releasing also the drum 44 which is geared thereto. As soon as the drum starts turning and before the pallet wheel has made one revolution, the drum flange 53, by its inclined surface, has forced the releasing lever through its pin 50 into an abnormal position where the stop pin 68 cannot meet the pallet wheel 69 and stop it until the drum completes its revolution. When this occurs, the pin 50 drops into the slot in the annular flange just before the pallet wheel pin comes to its normal position, causing the stop pin 68 to bring the pallet wheel to rest. The gearing is herein selected so that the pallet wheel makes four revolutions for each revolution of the drum. During the rotation of the drum, the pin 50 bears against the inner wall of the flange being held thereagainst by the spring 54 acting on the lever 51. It will thus be seen, that when once released, the drum will continue to turn until it completes one revolution, being always brought to rest by the stop pin on the pallet wheel in the same angular position.

To trip the release lever 51, the latter has a depending portion 55, the lower end of which lies opposite a laterally projecting pin 56 carried by one end of the armature lever 57, the latter being secured to the upper end of the armature shaft 58 and adapted to oscillate therewith when moved by the armature 59 connected to the lower end of the armature shaft (Figs. 3 and 5).

When the starting magnet 21 is energized, the armature (see Fig. 5) is attracted toward the magnet poles 60 against the tension of the retracting spring 61 and swings counter clockwise (as viewed in Fig. 5), turning the armature shaft and simultaneously swinging the armature lever 57, the pin 56 being thereupon brought into engagement with the end 55 of the release lever forcing the latter into the dotted line position shown in Fig. 4, and freeing the drum.

After the drum starts to turn, the signal is selected or differentiated, according as the break in the auxiliary circuit, which causes the energization of the magnet, is accidental or intentional. To control the sending of a signal indicating a line fault, there is provided a face cam 70 (see Figs. 3 and 7), which is mounted to turn upon the shaft 43

but rigidly connected to the drum 44 to turn therewith. The cam 70 is provided upon its face with an annular groove 71, and also with a short, segmental groove 72 opening into the annular groove and curved toward the centre of the cam. Working in the groove 71 is a lateral pin 73, carried by the signaling lever 74, the latter being connected to a hub 75 which turns freely upon the pallet wheel shaft 66. At the opposite end of the hub 75 (see Fig. 3), there is provided the depending finger piece 76, carrying the adjustable set screw 77, the end of which lies within the path of the left hand end (as viewed in Fig. 5) of the armature lever, so that, when the latter is moved by the energization of the magnet, the signaling lever 74 is forced in such a direction as to press the pin 73 against the inner wall of the annular cam groove 71, such pin being normally pressed against the outer wall thereof by means of the tension spring 78 connected to the depending finger piece 76.

If the break in the auxiliary circuit is a persisting break, indicating a fault in the line, the armature will remain attracted and the pin 73, being forced against the inner wall of the annular cam groove, will enter the segmental groove 72 when a sufficient interval has elapsed to bring the mouth of that groove opposite the pin on the signaling lever. If the break in the auxiliary circuit is caused by pulling one of the emergency switches 23, the circuit will be quickly closed again, and the armature released, causing the pin 73 again to press against the outer wall of the cam groove. The movement of the drum is retarded and timed by the pallet gearing so that a sufficient interval is provided between the release of the drum and the registration of the segmental groove with the pin 73 to prevent the pin 73 entering the segmental groove 72 except when the break in the auxiliary circuit persists longer than is provided for by the pulling of one of the emergency signaling switches 23.

Assuming that the auxiliary circuit has been accidentally broken and the energization of the starting magnet continues, the pin 73 will enter the segmental groove 72, and by further rotation of the drum and cam the lever 74 will be forcibly drawn toward the centre of the cam and towards an upright position. As the pin passes through the segmental groove and again enters the annular groove, the lever will reverse its movement and be returned again to its normal position, as shown in full lines in Fig. 7.

The rocking or tilting movement of the signaling lever which is thus caused by a persisting break in the auxiliary circuit, acts, first to open, and then again to close the main line contacts 27 (see Figs. 3 and 7),

this being effected by the pin 80 carried by the curved upper end 81 of the lever 74, and brought into lifting engagement with the overhanging end 82 of the upper one of the contacts 27. The main line circuit being thus temporarily interrupted, a single tap or signal is transmitted to the central station, which serves as a specific signal indicating the presence of a line fault on one of the auxiliary lines connected to the circuit.

If desired, this specific signal may be followed, or otherwise coupled with, the characteristic signal of the master box, thus indicating to the central station the particular auxiliary circuit which is at fault, or on the other hand, the apparatus may be so adjusted or constructed that the auxiliary pull mechanism in the box will be thrown into inoperative or a "not set" position, without any further signal being transmitted.

Herein the box starting attachment has means whereby it may be adjusted at will to send the specific signal alone or to follow it with the box signal. To that end, the hub 75, to which the selecting lever 74 is secured, has an outwardly directed projection or lug, 85, in which is mounted the adjustable set screw 86, underlying the end 87 of the box tripping link 20. If, on the rotation of the drum and cam, the pin 73 enters the segmental groove, the set screw 86 is lifted by movement of the lever 74 and raises the end 35 of the box tripping link, this serving to disconnect the same from the auxiliary pull mechanism. As shown in Fig. 7, the box tripping link has a shouldered portion 88 against which is normally pressed a pin 89, 40 carried by the box tripping cam lever 90. The latter is pivoted between the two ears 91 (Fig. 5) carried by the frame, and is actuated by the continued rotation of the drum, so as to press the pin 89 against the 45 shouldered portion of the box tripping link and move the same to trip the box.

When the adjusting screw 86 is adjusted to approximately the position shown in Fig. 7, the movement of the signaling lever 74 responsive to an accidental break in the auxiliary circuit lifts the end of the box tripping link 87 to such a height that the subsequent movement of the tripping lever, which follows shortly thereafter, will cause 55 the pin 89 to pass along the under edge of the link 87 without engagement with the shouldered portion thereof, and no further signal can be sent in addition to the specific trouble signal until the box is again set.

If the adjusting screw 86 is set so as to allow sufficient initial clearance between the end 87 of the box tripping link and the tip of the screw, the movement of the selecting lever 74 as the pin 73 enters the segmental groove 72 will have no effect on the box

tripping link, but the parts will remain in their normal position in readiness for actuation by the subsequent movement of the box tripping lever, and the specific signal will be followed by the individual signal of the station.

If the break in the auxiliary circuit is of short duration, such as follows the sending of an emergency signal from one of the stations on the auxiliary circuit, the armature lever will be restored to its normal position before the mouth of the segmental path is brought into registration with the pin 73, so that the latter, being no longer forced against the inner wall of the annular path, 80 will remain in that path and no movement of the lever 74 will result. Under these conditions, the drum will continue to rotate and the emergency signal will be given in the usual way by the movement of the box tripping lever 90.

In the course of the rotation of the drum, shortly after the mouth of the segmental groove 72 passes the pin 73, the box tripping lever 90 is thrown inwardly by means 90 of an actuating cam 95 (see Figs. 3 and 6). If the break is the result of an emergency signal, this acts to actuate the box tripping link 20. If the set screw 86 on the lever projection 85 is adjusted, to leave sufficient 95 clearance between the screw and the link 87 to prevent the prior disconnection of the link from the pin 89, the cam actuated movement of the lever 90 will also act to trip the box, even though the break be a permanent 100 break. The cam 95 is secured to one side of the drum 44 and has a cam surface 96, against which bears the lateral pin 97, carried on the lever 90, the pin being held outwardly against the cam surface by means 105 of the coiled spring 98 at the fulcrum of the lever (see Figs. 3 and 5).

The cam surface 96 is so shaped that when the drum has turned to a suitable point, the tripping lever is moved to the 110 left (as viewed in Fig. 6), being allowed to resume its normal position under the influence of the coiled spring 98 when the drum completes its revolution. When this point is reached the drum is brought to 115 rest by the release lever 51. It will, therefore, be seen that, with the drum wound up and set, the box tripping cam lever 90 will give one complete oscillation whenever the drum is released, and that this serves 120 to release the signaling train, or not, according to the duration of the break in the auxiliary circuit and the position of the adjusting screw 86.

Immediately after the mouth of the segmental path 72 passes the pin 73 in the course of the turning of the drum, the tripping magnet 21 is shunted.

This not only cuts out the resistance of the magnet from the main line, thereby in- 130

creasing the line current, but de-energizes the magnet, so that if the break in the auxiliary circuit is a permanent break, the armature lever is allowed to retract and free the releasing lever 51 to stop the drum at the end of one revolution. For this purpose, the normally open contacts 100 are provided (see Fig. 2) which are contained in a shunt circuit about the magnet 21, so that the closure of these contacts reduces the current through the magnet to an insignificant amount, whether the auxiliary circuit is opened or closed. These contacts 100 (Fig. 8) are normally held open by the lifting pressure of the pin 101, exerted against the under side of the overlying contact finger 102. If the pin 101 is withdrawn, the contacts 100 close and the magnet 21 becomes shunted. The pin 101 is carried by the curved end 103 of the shunt lever 104, which is pivoted at 105 upon the frame. The shunt lever is normally held in upright position to hold the contacts open by a holding arm 106, which has a notched portion 107 engaging a holding pin 108, projecting laterally from the side of the lever 104. When the holding arm 106 is depressed, a spring 109 secured to the curved end 110 of the holding lever, tends to throw the latter right-handedly as viewed in Fig. 8 (into the dotted line position shown), thereby closing the contacts 100. To depress the holding arm 106, at the appropriate time, the latter has an upright projection 111 which lies within the path of a radial projection 112 carried by a sleeve 113, fixedly secured to the drum 44, to turn therewith. In the rotation of the drum, the projection 112 strikes the projection 111 on the holding arm immediately after the mouth of the segmental groove 72 has passed the pin 73 on the selecting lever, and depresses the holding arm thereby releasing the shunt lever, and cutting out the auxiliary actuating magnet.

After the projection 112 has passed out of contact with the holding arm, the latter is again lifted by a tension spring 114, so that its edge is pressed against the lateral pin 108 in readiness to catch and to hold the same when the shunt lever is moved back to its upright position. After the box has been tripped, the starting attachment may be restored to its "set" or operative position by turning the end 47 of the drum shaft right-handedly (as viewed in Fig. 8) for one complete revolution as heretofore described, the drum being held fixed by the stop pin 68 on the release lever 51. This not only winds up the drum spring 45, but re-sets the shunt lever. For this purpose there is provided the sleeve 120, having the tooth 121, which sleeve is pinned or otherwise fastened to the drum shaft 43 to rotate therewith. With the drum spring unwound and the drum brought

to rest, and with the shunt lever released and thrown as described, when the drum shaft is turned to wind up the spring the projecting tooth 121 strikes the end of a dog lever 122 which has the shouldered head 123, normally pressed up against the sleeve 120 by the spring 109, one end of which is secured to a projection 124 on the dog lever 122. Depression of this lever causes a depending arm 125 of the dog lever to sweep down and, by engagement with a pin 126 projecting laterally from the shunt lever 104, throw the latter back to its upright position and there hold it locked by the holding arm 106. As the tooth 121 snaps past the shouldered head 123, the latter moves in front of the head and acts as a holding dog to prevent reverse movement of the drum shaft under the pull of the winding spring when the winding pressure is relieved. The winding movement of the drum shaft is limited to one complete turn by means of a stop pin 130 (Fig. 4) extending laterally from the side of the drum 44, and adapted to engage a stop finger 131 mounted on a sleeve 132 secured to the drum shaft. When the drum shaft is wound up it is brought to rest with the stop finger on the right hand side of the stop pin as shown in full lines in Fig. 4. After the drum has been released and completes its revolution the pin engages the opposite side of the stop finger 131 and moves it to the dotted line position shown due to a limited amount of play which the sleeve 132 has upon the shaft 43. To provide such play the sleeve is fastened to the shaft by means of the pin 133 working in a short slot 134 in the sleeve and providing a limited angular movement of the stop finger 131 with relation to the shaft, so that the drum when released makes one complete turn, and the shaft 43 makes one complete turn when the apparatus is re-set.

In order to show the condition of the starting attachment, an indicator device is employed adapted to give some indication such as the display of the word "set" when the attachment is in operative or "set" condition, and some contrary indication such as the display of the words "not set" when the attachment is in a run-down or un-set condition. For this purpose the shunt lever 104 has connected to its hub an upright arm 140 (see Figs. 1, 3 and 9) moved by and with the latter and adapted to actuate a shield 141. The latter is pivoted on the pallet wheel shaft 66 and has the slot 144 in which slides the pin 145 secured to the swinging arm 140, the relation of the parts being such that the shield moves from one position to another with the described movement of the shunt lever. In the position which the shield assumes when the shunt lever is upright it covers the word "not" on the annunciator plate 142 and leaves visible the word "set."

When the shunt lever is released following the excitation of the starting magnet, the shield moves to its opposite position and uncovers the word "not" so that the reading becomes "not set."

To avoid interference between signals from two different signaling stations on the same auxiliary circuit, a non-interfering locking lever 150 (Fig. 4) may be employed, the free end of which underlies the lower end of the releasing lever 55 and is pressed against the same by the tension spring 151. The magnet having been energized and the drum released by the movement of the releasing lever, the locking lever 150 remains in contact with the armature lever 57. As soon as the latter retracts, due to the subsequent de-energization of the starting magnet, the locking lever lifts and catches the armature lever 57 in the shouldered portion 152, preventing any further movement of the armature lever until the starting attachment has completed its cycle of operations. On the completion of the rotation of the drum, the reverse movement of the releasing lever depresses the locking lever 150 to a position where it no longer interferes with the movement of the armature lever 57, but it will be observed that the shunt lever, having been meanwhile released, the starting magnet is inoperative to effect any further actuation of the signaling mechanism until the starting attachment has been again reset.

The signaling switches 23 at the auxiliary stations are merely conventional representations of any well-known devices which provide preferably for the certain movement of some circuit breaking member as soon as an actuating device is moved, which member moves with certainty to a circuit restoring position after a short but definite interval. Such devices may be self-restoring, that is to say, where the movement of the actuator not only releases or moves the circuit breaking member but also supplies the power which is utilized to move it in its next succeeding movement or movements; or, the circuit breaking member may be actuated by means such as a spring, which is wound from time to time, and which serves to move the circuit breaking member, as described, when released by the actuator.

While I have herein shown and described for purposes of illustration one specific embodiment of the invention and have illustrated the same in connection with a normally closed auxiliary circuit employing the main line current in shunt to a box starting magnet, the invention as to many of its features is not limited to that particular application but is capable of a great variety of uses, and is not limited as to the form or relative arrangement of parts by which the same has been herein disclosed for purposes of illustration.

Claims:

1. In a fire alarm system having a main line circuit and an auxiliary loop on said circuit, a box starting attachment for a main line box provided with a starting magnet the windings of which are included in the main line circuit and shunted by said auxiliary loop, said attachment having means responsive to a temporary break in said auxiliary loop to start the box and also responsive to a continuing break in said loop to transmit a specific signal to the central station indicative of a line fault. 70
2. In a fire alarm system having a main line circuit and an auxiliary loop on said circuit, a box starting attachment for a main line box provided with a starting magnet the windings of which are included in the main line circuit and shunted by said auxiliary loop, said attachment having means 80 responsive to a temporary break in said auxiliary loop to start the box and also responsive to a continuing break in said loop to transmit a specific signal to the central station indicative of a line fault followed by 85 the starting of the box. 90
3. In a fire alarm system having a main line circuit and an auxiliary loop on said circuit, a box starting attachment for a main line box provided with a starting magnet the windings of which are included in the main line circuit and shunted by said auxiliary loop, said attachment having means 95 responsive to a temporary break in said auxiliary loop to start the box and also responsive to a continuing break in said loop to transmit a specific signal to the central station indicative of a line fault, and said attachment having means whereby it may be adjusted to cause said specific signal to be 100 transmitted alone or to be followed by the starting of the box. 105
4. A box starting attachment for use in the main line circuit of a fire alarm system and adapted to be controlled by a normally closed auxiliary circuit characterized by main line signaling devices in addition to the box, and selective controlling devices operable by a break in the auxiliary circuit for determining the starting of the box 110 alone or the actuation of said main line signaling devices dependent on the duration of the break in said circuit. 115
5. In a starting attachment for a main line signaling transmitter, said attachment comprising a tripping magnet the winding of which is serially connected with such transmitter, a main line signaling device aside from said transmitter, and means for rendering said device operable only during action of said attachment in response to prolonged energization of said magnet. 120
6. In a fire alarm system, a main line circuit, one or more main line signaling boxes 125

- each with a fire signal transmitting device and mechanism responsive to an auxiliary circuit and comprising tripping mechanism for said device, an auxiliary circuit controlling the responsive mechanism of one of said boxes, and means governed by said responsive mechanism and independent of said tripping mechanism for transmitting trouble signals through the main line circuit dependent on a prolonged break in the auxiliary circuit.
7. In a fire alarm system, a main line circuit, one or more signaling boxes with a signal transmitting device and mechanism responsive to an auxiliary circuit and comprising tripping mechanism for said device, an auxiliary circuit controlling the responsive mechanism of one of said boxes, one or more auxiliary signaling stations each with a circuit changing device operable to cause interruption of said auxiliary circuit for a predetermined brief interval, and means governed by said responsive mechanism and independent of said tripping mechanism for transmitting a trouble signal through the main line circuit dependent on a break in the auxiliary circuit continued longer than such predetermined interval.
8. A fire alarm system having a main line circuit and one or more signaling stations each with a main line transmitting device and mechanism responsive to an auxiliary circuit, and means governed by said responsive mechanism for transmitting a signal indicative of an auxiliary line fault and for tripping said device to cause transmission thereby of a signal indicating the particular line at fault.
9. In a starting attachment for a main line signal transmitter, said attachment provided with a starting magnet, a starting member for such a transmitter, means governed by said magnet whereby said member is operable by said attachment only when acting in response to a change in the electrical condition of said magnet having a certain predetermined characteristic, and means operable by said attachment other than through said member only in response to changes in the electrical condition of said magnet, which changes lack such predetermined characteristic, for formulating a specific signal in the current path of said magnet.
10. In a fire alarm system, a main line box comprising a signaling train and main line signaling mechanism comprising a magnet, means governed by said magnet arranged for causing response of said mechanism to current changing devices at signaling stations on an auxiliary circuit, said signaling mechanism comprising signaling devices, tripping means for said signaling train, and means to actuate said signaling devices without tripping the train, said means depending for its effectiveness on whether the current change in the auxiliary circuit has a certain predetermined characteristic.
11. In a main line fire alarm box having a signal transmitter and an attachment comprising a member for starting said transmitter, controlling means for said attachment arranged for response to an auxiliary line circuit, signaling means in addition to said transmitter, and means responsive to said attachment for actuating said signaling means in the event of a prolonged break in the auxiliary circuit.
12. A fire alarm system in combination with a main line circuit and signaling mechanism therein, a controlling magnet in the main line circuit, a normally closed auxiliary loop in shunt to said magnet, a box starting attachment having actuating means adapted to be set in motion by the controlling magnet and having a retarded movement, and means actuated by the movement thereof to send a specific alarm on the continued energization of the magnet but to start the box on a temporary energization thereof.
13. A fire alarm system having a main line circuit and an auxiliary circuit, a starting attachment for a main line box controlled by the auxiliary circuit, circuit breaking means for temporarily opening the main line circuit, said means including a circuit breaking member and a two path cam to move said member together with cam moving means, said member when controlled by one path of the cam being moved to break the circuit, and when controlled by the other path of the cam being held in non-circuit breaking relation, and a box starting magnet with its armature, said member being controlled by the one path or other of the cam according to the position of the armature.
14. A starting device for the signaling train of a main line circuit fire alarm box adapted to be controlled by an auxiliary circuit and comprising starting mechanism for the signaling train, motive means for controlling said starting mechanism, said motive means having a retarded movement, an auxiliary circuit and means controllable by said auxiliary circuit to set said motive means in operation but also controlled by said auxiliary circuit to prevent the starting of the box after said motive means has been set into operation.
15. A starting mechanism for a main line box of a fire alarm system adapted to be controlled by an auxiliary circuit, the same comprising a starting member, motive means adapted when released to have a retarded movement, an auxiliary circuit releasing means, a starting magnet adapted to control said releasing means, said starting mag-

net being controllable through said auxiliary circuit, and means controlled by said starting magnet for rendering the motive means ineffective to actuate the starting member after the motive means has been released. 70

16. A device for starting the signaling train of a main line box for a fire alarm system comprising actuating motive means, including a shaft and a spring connected drum, releasing means and means to give a retarded movement to said drum when released, a starting magnet adapted to control said releasing means and start said motive means into operation, and means for rendering said motive means ineffective to actuate the signaling train after the drum has been released. 75

17. In a fire alarm system, a main line circuit having one or more signaling stations with signaling mechanism, a controlling magnet for said signaling mechanism, said magnet being in the main line circuit, an auxiliary circuit controlling said magnet, mechanism to actuate said signaling mechanism and adapted to be set in operation by said magnet, means controlled by said mechanism to send a specific signal in the event of a permanent break in the auxiliary circuit and means for diverting the main line current from said magnet after said mechanism has been set in operation. 80

18. In a fire alarm system, the combination with a main line circuit, of a signaling box, an auxiliary circuit having a plurality of stations, a main line transmitter at the signaling box, a starting attachment for said transmitter, said attachment comprising a magnet responsive to said auxiliary circuit, means governed by said magnet for causing response of said attachment to changes in the electrical condition of said auxiliary circuit, a member for starting said transmitter, means operable by said attachment whereby said member will be subjected to actuation only when acting in response to a change in the electrical condition of said magnet having a certain predetermined time characteristic, and means rendered effective by and during the action of said attachment in response to a change in the electrical condition of said magnet having such predetermined time characteristics for preventing response of said attachment to subsequent changes in the condition of said magnet. 90

19. A fire alarm system having a main line circuit, a main line box, an auxiliary circuit with a plurality of sending stations therein, signaling mechanism including a box starting attachment provided with a starting magnet controlled by said auxiliary circuit, and including also means operable through said magnet for sending a specific signal in the event of a line fault on said auxiliary circuit, said means having provision, rendered effective by, and during the action of said attachment in response to, a predetermined cycle of changes in the electrical condition of said magnet, for preventing response of said attachment to subsequent changes in the condition of said magnet. 95

20. In a starting attachment for a main line signal transmitter, said attachment provided with a starting magnet, a starting member for such a transmitter, means governed by said magnet whereby said member is operable by said attachment only when acting in response to a change in the electrical condition of said magnet having a certain predetermined time characteristic, said means having provision rendered effective by and during the action of said attachment in response to a change in the electrical condition of said magnet having such predetermined time characteristic, for preventing response of said attachment to subsequent changes in the condition of said magnet. 100

21. In a fire alarm system, the combination of a main line circuit having a signaling box, a normally closed auxiliary circuit, a starting magnet in the main line circuit, controllable by said auxiliary circuit, means governed by said magnet for causing response of said box in the event of abnormal conditioning of said auxiliary circuit for not to exceed a predetermined interval, and line fault responsive means governed by the action of said starting magnet in response to abnormal conditioning of said auxiliary circuit for a greater interval, said means acting after the lapse of such a greater interval to render the magnet unresponsive to main line current flow. 105

22. In a fire alarm system having an auxiliary circuit and a box starting magnet controlled thereby, said magnet being in the main line circuit, a magnet controlled attachment comprising box starting means, and an auxiliary line fault responsive device for cutting out the resistance of the magnet windings, said device being operable independently of said means. 110

23. A fire alarm system having a main line circuit and a normally closed auxiliary circuit with a box starting attachment, the latter having a set and an unset condition and comprising means for changing the condition of said attachment from set to unset and for effectuating said change in the condition of said attachment responsive to said auxiliary circuit to thereby start a main line box and also responsive to a line fault in said auxiliary circuit to thereby send a specific signal. 115

24. A fire alarm system having a main line circuit and a normally closed auxiliary circuit, a box starting attachment, the latter 120

having a set and unset position, with mechanism for actuating said attachment including devices controlled by the auxiliary circuit for starting the box when in its set position, and devices for sending a specific signal over the main line circuit indicative of an auxiliary line fault and for throwing the attachment to an unset position.

25. A fire alarm system having a main line circuit and a normally closed auxiliary circuit with a box starting attachment, said attachment comprising a member having a set and an unset position and devices controllable by said auxiliary circuit to cause movement of said member from its set to its unset position, said devices comprising means selectively controllable by said auxiliary circuit for sending a specific signal and accomplishing such movement without otherwise effective actuation of the box starting attachment.

26. In a fire alarm system, the combination with a main line circuit, an auxiliary circuit with a plurality of signaling stations thereon, signaling mechanism controlled by said auxiliary circuit including a signaling train adapted to be released to transmit a characteristic signal over the main line and means for transmitting over the main line a specific signal indicative of a line fault, controlling devices for said signaling mechanism including a magnet in the main line circuit, said auxiliary circuit being in shunt to said magnet, a motive device for starting the train adapted to be set in operation by the energization of said magnet due to breaking the auxiliary circuit at a signaling station but ineffective to start the train until after the lapse of a substantial interval, means operated by the energization of the magnet at the end of a shorter interval following the operation of the motive device for transmitting the specific signal, and means after the motive device has been started under the control of one signal station for preventing the reenergization of the magnet through a second station from actuating said specific signal transmitting means.

27. In a fire alarm system having a main line circuit and an auxiliary circuit with a plurality of signaling stations thereon, a box starting attachment for a fire alarm system adapted to be controlled by an auxiliary circuit having a motive device for starting the box adapted to be set in operation by the breaking of the circuit but ineffective to start the box until after the lapse of a substantial interval, means operated by the presence of a break in said circuit at the end of a shorter interval following the operation of the motive device for transmitting a different signal, and means, after the motive device has been started and the auxiliary

circuit again closed, for preventing a succeeding break in the circuit from actuating said different signal transmitting means.

28. In a fire alarm system having an auxiliary circuit and a box starting magnet controlled thereby, said magnet being in the main line circuit, a box starting member, an auxiliary-line-fault responsive device, and means responsive to said magnet for controlling said box starting member and operable independent of said box starting member for shunting the magnet windings.

29. In a starting attachment for a main line signal transmitter, said attachment provided with a starting magnet, a member for starting an associated transmitter, mechanism for operating said member from said starting magnet, and means operable other than through said member for formulating a signal only when said attachment is acting in response to energization of said magnet continued in excess of a predetermined interval.

30. In a starting attachment for a main line signal transmitter, said attachment provided with a starting magnet, member operable for starting an associated transmitter, and mechanism responsive to energization of said starting magnet for not to exceed a predetermined interval to actuate said starting member and said attachment including also signal formulating devices responsive to energization of said starting magnet continued for a time substantially longer than said predetermined interval to act to formulate a signal.

31. In a starting attachment for a main line signal transmitter, said attachment provided with a starting magnet, member operable for starting an associated transmitter, signal formulating means subject to actuation by said attachment, and a determining device governed by said magnet and operable by said attachment said determining device having provision whereby said formulating means will be actuated to formulate its signal only when said magnet is effectively energized at a predetermined point in the operation of said attachment.

32. In a starting attachment for a main line signal transmitter, said attachment provided with a starting magnet, means including a starting member operable for starting an associated transmitter, signal formulating means subject to actuation by said attachment, and a determining device governed by said magnet and operable by said attachment, said determining device having provision whereby said starting member will be actuated only when said magnet is not effectively energized at a predetermined point in the operation of said attachment and having also provision whereby said formulating means will be actuated to formu-

late its signal only when said magnet is effectively energized at such predetermined point.

33. In a starting attachment for a main line signal transmitter, said attachment provided with a starting magnet, means including a starting member operable by said attachment for starting an associated transmitter only when acting in response to energization of said magnet the duration of which does not exceed a predetermined interval, and means operable by said attachment independent of said starting member for formulating a signal only when said attachment is acting in response to energization of said starting magnet the duration of which exceeds such predetermined interval.

34. In a starting attachment for a main line signal transmitter, said attachment provided with a starting magnet, means including a starting member operable for starting an associated transmitter and signal formulating means each independently operable by said attachment, electrical conductors for serially connecting said starting magnet and said formulating means with each other and with such a transmitter, and a determining device comprising a controlling member and a retarded operated member, said controlling member governed by said starting magnet and said retarded member being arranged to engage said controlling member to cause actuation of said formulating means only when said controlling member is abnormally positioned at the termination of a predetermined interval measured by the movement of said retarded member.

35. In a signaling system comprising a main line signal circuit, a code signal transmitter included in said circuit, a starting attachment for said transmitter having a tripping magnet the winding of which is included in said circuit, a comparatively low

resistance shunting loop for said magnet 45 winding, and a plurality of auxiliary stations included in said loop and each having mechanism arranged to break said loop for a certain predetermined period following actuation thereof and to thereupon close 50 such break, the combination of means responsive to the action of said attachment for starting said transmitter only when said attachment is acting in response to energization of said tripping magnet, the duration of which does not substantially exceed that of a shunt loop break incident to the actuation of any auxiliary station and also operable by the action of said attachment to formulate a signal in said circuit only 60 when said attachment is acting in response to energization of said tripping magnet continued for a period substantially greater than that of the shunt loop break incident to the actuation of any auxiliary station. 65

36. In a starting attachment for a main line signal transmitter, said attachment provided with a starting magnet, means including a starting member operable for starting an associated transmitter and signal formulating means, said means being subject each to independent actuation by said attachment. 70

37. In a starting attachment for a main line signal transmitter, said attachment provided with a starting magnet, a member for starting such a transmitter operable by said attachment only when acting in response to abnormal conditioning of said magnet for not to exceed a predetermined interval, 80 and means rendered effective by and during the action of said attachment for preventing response during any cycle of the action thereof to a repeated abnormal conditioning of said magnet. 85

In testimony whereof, I have signed my name to this specification.

NATHAN H. SUREN.

Certificate of Correction.

It is hereby certified that in Letters Patent No. 1,503,439, granted July 29, 1924, upon the application of Nathan H. Suren, of Needham, Massachusetts, for an improvement in "Fire-Alarm Systems," errors appear in the printed specification requiring correction as follows: Page 9, line 90, claim 30, and line 103, claim 31, after the word "magnet" insert the words *including a starting*; and line 112, for the misspelled word *predetermined* and *predetermined*; and that the said Letters Patent should be read with these corrections therein so that the same may conform to the record of the case in the Patent Office.

Signed and sealed this 2d day of September, 1924.

[SEAL.]

KARL FENNING,
Acting Commissioner of Patents.
